UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

1,324,089.

Specification of Letters Patent.

Patented Dec. 9, 1919.

Application filed April 12, 1919. Serial No. 289,630.

To all whom it may concern:

Be it known that I, FRANKLIN R. WHITE, a citizen of the United States, and a resident of Waterbury, in the county of New Haven and State of Connecticut, have made and invented certain new and useful Improvements in Buttons, of which the following is a specification.

My invention relates to a new and useful improvement in buttons, and particularly to that kind or type known and referred to as swivel or flexible buttons, and is similar to a button for which I have executed an application of even date herewith. It is also similar to that type of button shown in the patent granted to Leonard R. Carley, No. 1,191,944, and patented on July 23, 1916.

In the present invention, however, the base is different from that shown in the patent to Carley, and is different from the application filed of even date herewith, in that the present invention shows a button to be used with a tack instead of a staple.

Buttons of this character, although constructed on the same principles, necessitate different impressed or dented walls when used with a tack rather than with a staple, as when a staple is used it is necessary to so shape the walls of the anchors or anchor that the prongs of the staple will remain spaced throughout their upward movement into their final position; whereas when the fastening means is in the form of a tack rather than a staple this spacing is not necessary, it simply being desired to keep the tack in a vertical plane during its upward movement.

An object of the present invention is to provide a flexible swivel button wherein a head and base are employed, and wherein after the base is placed in the head the upper edge of the base is forced slightly outwardly to extend beyond an inwardly extending rim formed on the body of the head so that the head may move vertically, rotatably, and laterally, with relation to the base but cannot become disengaged therefrom.

Still another object of my invention is to provide a flexible button having an imperforate base which is to be pierced by the prong of a tack to tightly hold the button with relation to the cloth to which it is to be attached and to so form the base that the prong of the tack will be correctly guided in its upward movement to pierce the center

of the base, impinge against an anvil located in the head of the button where it is to be deflected, and then extend downwardly and contact and practically lock against the slanting central wall of the top portion of 60 the base.

Still another object of my invention is to provide a button that is to be employed with a tack fastener that will rigidly hold the base with relation to the cloth to which it 65 is to be attached and at the same time allow the head of the button to tilt and rotate; or, in other words, to procure a button of great flexibility.

With these and other objects in view, my 70 invention consists in certain new and novel features of construction and combinations of parts as will be hereinafter more fully described and pointed out in the claims.

Referring now to the drawings forming 75 a part of the invention:

Figure 1 is a sectional view of my improved flexible button showing the base and head in section, the upper edge of the base having been forced downwardly or flared 80 after being inserted; the staple being shown in elevation and before its entry into the base of the button;

Fig. 2 is a similar view showing the tack in its final position, the upper edge of the 85 base having been flared and the tack deflected to its final locking position;

Fig. 3 is a fragmentary view of the base of the button showing the upper edge in its position before being flared; 90

Fig. 4 is a top plan of the assembled button, a portion of the anvil and top plate being broken away for the sake of clearness;

Fig. 5 is a sectional view of a modified form of the base; 95

Fig. 6 is a sectional view of a further modification of the base;

Fig. 7 is a perspective of the anchor as used in the modification shown in Fig. 6.

Referring now to Figs. 1 to 4 of the 100 drawings, it will be seen that the button comprises a head 1 having the downwardly extending hub 2 in the form of a hollow shell and having the open restricted bottom 3 which is obtained by bending the walls of 105 the hub 2 inwardly as at 4. The upper edge of the body portion 1 is flared outwardly as at 5, so that when completing the button the edges of a top plate 6 may be forced downwardly over the flared portion 4 to thereby 110

clamp the body of the button. An anvil 7 is placed in the button to deflect the prong of a tack 8 when the same is inserted in the button, so that the tack will not pierce the 5 top plate 6, but, on the other hand, will be properly deflected. A base 9 is shown which is provided with an outwardly extending rim 10, which rim is turned upwardly and slightly inwardly as at 11. The base is 10 provided with a central hub portion 12 and having the imperforate top plate 13 which doubles back into the hub as at 14 and is then struck up from beneath, forming the raised central portion 15.

15 The purpose of forming this centrally locked raised portion is to properly guide the point of the tack 8 when it is forced through the cloth and up into the base, as it often happens in buttons of a similar construction that the tack will not be exactly vertically alined when being forced through the cloth and will therefore deflect and not pierce the head of the anchor or base, as desired. By providing the top plate of the 20 base as shown, however, should the point of the tack be incorrectly alined, when it impinges against this plate it will be guided by the upwardly extending walls of the raised portion 15 and pierce the desired center.

25 30 The purpose of doubling the wall 14 back in the hub is that it will allow the circular edge 16 to be flared or forced outwardly as shown at 18 and not subject the top of the hub to a breaking or fracturing strain, which 35 would be the case if the top were perfectly flat.

In assembling the button the hub of the base will be inserted within the restricted open bottom of the hub of the button, the diameter of the opening being slightly greater 40 than the diameter of the hub of the base, and after so inserted the upper circular edge 16 of the base will be forced downwardly and outwardly as at 18 and as previously referred to. The anvil 7 will then be inserted 45 in the top of the button and the top plate 6 closed on the rim 5.

The base will then be placed on the cloth to which it is to be attached and the tack 8 placed thereunder and the point thereof forced through the cloth. The point, if not 50 correctly alined, will impinge against the walls of the top plate and be directed centrally to the apex 15, and after piercing the same will impinge against the anvil 7 and will there be deflected and flattened over the wall of the top plate 13 and locked, as 55 clearly shown in Fig. 2, the point of the tack having a relatively large bearing surface on the upper portion of the top plate 13. The head of the button may now move vertically 60 with relation to the base, may tilt, or may swivel, as is desired; the base of the button being rigidly and securely fastened 65 to the cloth, and the flared upper edges of

the base will prevent the head from being detached as the circular edges 18 will extend beyond the center edges of the wall 4 of the head.

Referring now to the modified form shown 70 in Fig. 5, it is to be understood that the head of the button will remain the same, the base, however, being of a different construction. In this instance the base 20 comprises the upwardly extending hub 21, a portion of the 75 same 22 being doubled into the hub, and the plate 23 being forced upwardly in its center as at 25, similar to the preferred form. The bottom, however, is flanged outwardly as at 25, and a separate base plate 26 is provided, 80 the diameter of which is slightly greater than the diameter of the rim 25. By using this extra plate 26, which is also forced upwardly as at 28 at its center, the point of the tack 8 will be correctly alined on entering 85 the same, and it provides another locking point with the tack and would overcome any great faulty alinement of the tack, which possibly might not be taken care of if the base were constructed as in the preferred 90 form.

The modified form shown in Fig. 6 is also somewhat similar, but in this instance the base 30 is provided with the downwardly extending portion 31 which is doubled into 95 the hub as in the previous forms and is forced upwardly in its center as at 32, the lower portion, however, extending outwardly as at 33 and upwardly as at 34. Within this hub and from the bottom is 100 wedged an anchor 35 having the side walls 36 and the upwardly extending central portion 37.

In both of these forms, as shown in Figs. 5 and 6, it will be understood that after the 105 same are placed in the head of the button the upper edges will be forced downwardly as in the preferred form, to retain the head and button in their positions.

From the foregoing it will be understood 110 that I have provided a flexible swivel button that is to be used with a tack fastener that will properly guide the tack in its upward movement to pierce the imperforate walls and to so construct the base that the 115 top portion and upper edge of the base will not be subjected to a breaking strain when the same is rimmed or flared outwardly to retain the head on the base. Furthermore, two thicknesses of metal coöperate 120 with the restricted opening of the head of the button, and the imperforate plate by being pressed upwardly at its center will also present a maximum amount of surface to the prong of the tack after it has been 125 deflected.

It will be understood that many slight changes may be made without departing from the spirit and scope of the invention.

Having thus described and explained my 130

invention, I claim and desire to secure by Letters Patent:

1. A swivel type button comprising a head having a restricted opening, a base having an imperforate top fitting within said opening and having a rimmed edge larger than the restricted opening, and said top being pressed upwardly from its sides toward its center.
- 10 2. A swivel type button comprising a head, said head having a hub with a restricted open bottom, a base having a hub of less diameter than the restricted opening fitting within said head and having its upper edge forced outwardly to lock the head with relation to the base, said base having an integral imperforate top and pressed upwardly from beneath to an apex.
- 20 3. A flexible button comprising a head, a base having an imperforate top passed into said head and its upper edge formed to coöperate with the head to allow a vertical movement within set limits, and the top plate being pressed upwardly to a center.
- 25 4. A flexible button comprising a head having a restricted opening, a base having an imperforate top, said base fitting within said opening and having a flared edge larger than the restricted opening in the head, and said top being bent downwardly into the base and having its central portion forced upwardly to provide sloping walls to its sides.
- 30 5. A swivel button comprising a head

with a restricted open bottom, a base 35 slipped within the head and the base provided with an imperforate rolled edge top to retain the base within the head, said top of the base being pressed upwardly to a center, and an anchor located in said 40 base and having a similar central indentation.

6. A swivel button comprising a head with a restricted open bottom, a base within said head having an imperforate top 45 and its upper circular edge pressed beyond the sides of the restricted opening in the head, and the top plate of the base being forced upwardly to provide sloping walls; an anvil located above said base in said 50 head, and a top plate secured to said head.

7. A button comprising a head, an anvil located therein, and a top plate secured to the body portion of the button; a base 55 slidably held in said head and held against disengagement therefrom, said base being provided with an imperforate top, the walls, however, slanting toward a central point, and an anchor in said base also provided with sloping walls toward a central point. 60

Signed at Waterbury, in the county of New Haven and State of Connecticut, this 3rd day of April A. D. 1919.
